FENDER ORNAMENT FOR AN AUTOMOBILE OR THE LIKE

George W. Walker, Bloomfield Hills, Mich., assignor to Ford Motor Company, Dearborn, Mich., a corporation of Delaware

Filed Nov. 25, 1960, Ser. No. 62,972

Term of patent 7 years

(Cl. D14—6)

FIG. 2

FIG. 1

FIG. 3

FIG. 6

FIG. 5

FIG. 8

FIG. 7

FIG. 10

FIG. 9

FIG. 4

FIG. 1 is a side elevational view of a fender ornament for automobiles or the like, showing my new design;

FIG. 2 is a top view;

FIG. 3 is a bottom view;

FIG. 4 is a perspective view; and

FIGS. 5, 6, 7, 8, 9 and 10 are sectional views taken on the planes indicated by the lines 5—5, 6—6, 7—7, 8—8, 9—9 and 10—10 of FIG. 1.

I claim:

The ornamental design for a fender ornament for an automobile or the like, substantially as shown.
